(57) **CLAIM**

The ornamental design for a combined facial recognition device and support, as shown and described.

DESCRIPTION

FIG. 1 is a front perspective view of a combined facial recognition device and support showing our design; FIG. 2 is a rear perspective view of FIG. 1; FIG. 3 is a front elevational view of FIG. 1; FIG. 4 is a rear elevational view of FIG. 1; FIG. 5 is a left-side elevational view of FIG. 1; FIG. 6 is a right-side elevational view of FIG. 1; FIG. 7 is a top plan view of FIG. 1; and, FIG. 8 is a bottom plan view of FIG. 1.

The broken lines shown in the drawings illustrate portions of the combined facial recognition device and support that form no part of the claimed design.
